UNITED STATES PATENT OFFICE.

LEANDER H. LA CHANCE AND GEORGE BROWNING, OF CHICAGO, ILLINOIS.

RAZOR.

1,361,266.

Specification of Letters Patent.

Patented Dec. 7, 1920.

Application filed July 8, 1920. Serial No. 394,669.

To all whom it may concern:

Be it known that we, LEANDER H. LA CHANCE, a citizen of the United States, and GEORGE BROWNING, a subject of the King of Great Britain, both residing at Chicago, in the county of Cook and State of Illinois, have invented certain new and useful Improvements in Razors, of which the following is a specification, reference being had to the accompanying drawings, forming a part thereof.

The purpose of this invention is to provide an improved construction of safety razor in which the blade is given an end-wise reciprocation by which a draw-cut is obtained from a direct forward movement of the blade over the surface to be shaved. It consists in the elements and features of construction shown and described, as indicated in the claims.

20 In the drawings:

Figure 1 is a face side elevation of a razor embodying this invention.

Fig. 2 is substantially an elevation from the opposite side showing the handle cut in section as to the line, 2—2, on Fig. 3.

Fig. 3 is a section at the line, 3—3, on Fig. 1.

Fig. 4 is an end elevation showing the housing partly broken away to disclose interior parts.

Fig. 5 is a section at the line, 5—5, on Fig. 4.

Fig. 6 is a section at the line 6—6, on Fig. 5.

Fig. 7 is a plan view of the blade.

Fig. 8 is a plan view of the comb guard.

Fig. 9 is an inverted plan view of a modification for cheapening the construction and facilitating the assembling.

Fig. 10 is a plan view of the guard and a bracket rigid therewith pertaining to said modification.

Fig. 11 is a section at the line, 11—11, on Fig. 10.

Fig. 12 is a plan view of a bracket and interiorly formed parts including securing for the handle.

Fig. 13 is a partly sectional plan view of the cover or retaining plate, section being made axially through a certain spring housing which it carries.

Fig. 14 is an end elevation of the guard plate and bracket rigid therewith with the roller mounted as to one of its bearings on said bracket.

Fig. 15 is an end elevation of the remainder of the structure assembled ready for completing the assembly by properly engaging the two assemblies of Figs. 14 and 15. 60

Fig. 16 is a section at the line, 16—16, on Fig. 1.

The razor shown in Figs. 1 to 8 inclusive of the drawings comprises a mount which constitutes a housing or inclosure for the operating parts having a handle, 2, projecting obliquely with respect to the plane of the blade mounted upon one wall of the housing as hereinafter described. The housing is open at the forward side, meaning the side in the direction of the movement of the razor in shaving, and is closed at what may be called the face side,—that is, the side toward the face in the operation of the razor, by the guard plate, 6, which constitutes an essential element of the mount and which has its forward edge in the form of a comb as shown at 6^a. This guard plate extends beyond the chamber of the housing at both ends, the projection at each end being nearly equal to the length of the housing chamber, to form a seat upon which the blade is lodged and reciprocated in its operation as hereinafter described. The guard plate is positioned on and secured to the remainder of the mount by a rectangular projection, 6^b, at the rear which extends between the lugs of the retaining plate hereinafter described, and has its rear edge abutting against the rear wall of the housing 80

85 which is projected up from the end walls at 1^a to form a stop and positioning means for the guard plate. A post, 10, rigid with the bottom of the housing and standing up within the chamber of the housing affords 90 means for securing the guard plate by means of the screw, 12, set through a countersunk aperture, 6^d, in the guard plate, the head of the screw being flush with the outer or face side of said plate. At the forward 100

side the end walls, 1^b, 1^b, of the housing being the end brackets of the mount, are extended to form lugs, 1^a, 1^a, to afford journal bearings for a crank shaft, 3, having intermediate its ends a crank, 3^a, and rigid 105 with it at opposite sides of the crank, rollers, 4, 4, having knurled peripheries for giving them adequate rolling engagement with the face of the user in shaving to cause the crank shaft to be rotated by the movement of the implement over the face. A pitman, 4^a, is connected to the crank, 3^a,

110

and extends rearwardly into the housing through the forward open side thereof. The crank shaft is most conveniently made unitarily with the roll member by setting 5 centrally into the outer ends of the rolls trunnion screws whose heads are seen at 3^b and rigidly joining the two spaced rolls by the crank wrist set rigidly into them eccentrically thereof. This pitman has a rack, 10 4^b, at one edge for engaging a pinion, 5, journaled on the mount by trunnions, 5^a, 5^a, engaging bearings respectively in the one side wall of the housing, and in the guard plate, 6. For positioning and guiding the pitman to maintain its rack, 4^b, in engagement 15 with the pinion, the post, 10, is reduced in diameter at its forward end by a rabbet bounded by the faces, 10^a and 10^b, upon which respectively the face and the edge opposite 20 the rack of the pitman, 4, are seated in the reciprocation of the pitman by the crank. The guidance and retention of the pitman in its proper path is completed by extending it past the pinion under the pintle, 11, by 25 which the retaining plate, hereinafter described, is hinged to the mount. The pinion, 5, is provided with what may be called a crank pin or eccentric pin, 5^b, which projects through an arc slot, 6^e, in the guard 30 plate, 6, and engages a transversely extending slot, 7^b, in the blade, 7, which is lodged upon the outer face of the guard plate, 6, and guided for longitudinal reciprocation thereon by means of studs, 6^c, projecting 35 from the guard plates and engaging longitudinal slots, 7^c, in the blade. For retaining the blade on the outer face of the guard plate there is provided a hinged retaining plate, 8, which is hinged to the mount by 40 means of lugs, 8^a, folded back from the opposite sides of the rearward projection, 8^b, with which the retaining plate is provided, the lugs embracing the mount at the rear part and being pivoted thereto by the pintle, 45 11, above mentioned which for convenience of assembling is made in the form of a bolt which has a reduced threaded end, 11^a, and slotted head, 11^b, and is inserted through a suitably large aperture with which the right 50 hand lug, 8^a, is provided, and through corresponding apertures in the end wall of the housing, and screwed into a smaller threaded aperture in the opposite lug, 8^a, as seen clearly in Fig. 5, being made fast by screwing 55 it into the shoulder formed by the reduction of the threaded end. The lugs, 8^a, 8^a, are spaced apart sufficiently to provide a small clearance, as seen in Fig. 5, between the right hand end lug and the end, 1^b, of 60 the housing, and a coiled spring, 9, is coiled about the pintle between said end and said lug, acting to hold the opposite lug snugly against the opposite end, 1^b. Said opposite lug is provided with a slight projection, 8^c, 65 on its inner face, which may be made by

merely striking the metal through with a punch from the outer side about half the thickness of the metal, thereby producing a projection equal to half the thickness of the metal at the inner side. This projection 70 engages a hole, 11^c, in the end, 1^b, said projection and hole being relatively positioned so as to be engaged when the retaining plate is in plate-retaining position as seen in Figs. 3 and 4. The retaining plate has at its opposite ends slight projections, 8^e, which lodge upon the outer face of the guard plate and thereby space the retaining plate away from the guard plate sufficiently to insure free path for the blade in its reciprocation without binding pressure between the retaining plate and guard plate. Preferably the ends of the guard plate are cut back slightly as seen at 6^f, so as not to project at either end beyond the path of the 80 blade in its reciprocation; and so that the blade is very slightly longer than its seat on the plate, so that each stroke of the blade will clean off from the face of the guard plate any lather or other material which 85 may have lodged thereon; and also for convenience of applying and removing the blade. The projections, 8^e, of the guard plate, which are most conveniently formed by bending down the sheet metal of which 90 the guard plate is most desirably made, affords convenient means by which the user may press the retaining plate, 8, longitudinally to disengage the projection, 8^e, from the aperture, 11^d, of the housing for releasing the retaining plate to permit it to be 95 folded back for removing the blade.

Upon considering the construction above described, it will be seen that in the operation of shaving the movement of the tool 105 over the face, rotating the roller, 4, and reciprocating the pitman, 4^a, oscillates the pinion, 5, and causes longitudinal reciprocation of the blade while it is advancing directly over the surface to be shaved, and that 110 thereby without any attention of the operator, there results a draw-cut of the blade, greatly improving its cutting action. In order that the blade may be reversed side for side, so as to present either side to the 115 face, as is desirable in order that advantage may be taken of slight differences which sometimes result from the method of honing, in relation of the cutting edge to the one face or the other, the blade is provided 120 with two apertures, 7^b, symmetrically situated with respect to a middle transverse line so that either aperture may be engaged by the crank pin, 5^b, of the pinion.

I am aware that heretofore razors have 125 been made having a roller for rolling over the surface to be shaved, and having connections by which a longitudinal reciprocation of the blade is derived from this rolling. But in all such constructions hereto- 130

fore, the connection of the roller with the blade for reciprocating the latter has not been such as to afford what I regard as an adequate length of stroke to the blade, with 5 perfect clearance between the roller and the blade which is necessary for preventing the device from becoming clogged with lather and hair, and with the roller in such position as to permit an adequate range of tilting of 10 the blade with respect to the surface being shaved, as required by convenience of operation, without liability of lifting the blade from the surface by fulcruming over the roller. The present device avoids all these 15 defects of and objections to former devices employing the roller for a like purpose.

In Figs. 9 to 16 inclusive, there is illustrated a form of this invention which is somewhat preferable from a manufacturing 20 standpoint, being less expensive to construct, and also having some advantages of compactness and consequent lightness, rendering it more acceptable to the user.

To these ends the construction differs 25 from that shown in preceding figures, as will appear from the following detailed description.

The mount is reduced to the guard plate and brackets, 101, 102, in which the roller 30 member, 4, is journaled and projections rigid with said brackets. One of said brackets, 101, is rigidly secured to the guard plate, 106; and the other bracket, 102, is formed integrally with a tie plate, 103, which 35 engages the ends of two studs, 104 and 105, which are rooted rigidly in the guard plate, 106, the stud, 104, serving as the journal shaft for the pinion, 5, while the other stud, 105, corresponds to the part, 10, of the first 40 described construction, and has a groove, 105^a, for guiding engagement of the pitman, 4^a, at the edge opposite the rack, 4^b, thus dispensing with the guidance and retention of the rack which in the eariler described 45 figures is afforded by the shaft, 11. The integral member comprising the bracket, 102, with the tie plate, 103, has the back flange, 112, formed by folding the sheet metal of which said integral member is formed at 50 a right angle to the bracket, 102, the tie plate being formed by folding from the back plate in a plane at right angles both to the bracket, 102, and to the back flange, 112. The handle is attached by means of a 55 threaded stud 113, rooted in the tie plate, 103, and inclined at an angle to said tie plate suitable for the protection of the handle.

The roller member and crank shaft in the 60 form shown in these Figs. 9 to 15, is made substantially unitary, each of the two separate roll members having at the outer end a trunnion or pintle projection, 4^c, the two roll members being rigidly connected by the 65 crank wrist, 4^y, set into said roll members

eccentrically thereof, and rendered substantially integral therewith by brazing or equivalent method.

The bracket, 102, which is integral with the tie plate, 103, has an outwardly-projecting hinge pintle, 115, for the cover plate; and the bracket, 101, which is rigid with the guard has alined with said hinge pintle, a threaded hole, 116.

The cover plate is preferably made so as 75 to afford clear space between it and the guard plate for unhindered reciprocation of the blade, and at the same time for holding the blade suitably seated on the guard plate, by the detail construction as follows: At 80 the forward edge it is bent at an oblique angle at 117^a to form a lip, 117^b, closely approaching or bearing lightly upon the blade lodged on the guard plate. It is folded at right angles at 117^c to form the back flange, 85 117^d, and again folded at right angles at opposite ends to form the lugs, 117^e, corresponding functionally to the lugs, 11^e, of the other form, for embracing between them brackets, 101, 102, corresponding to lugs, 90 11^e, of the other form.

The blade-guiding studs, 6^c, are enough 95 higher than the thickness of the blade to space the forward lip, 117^b, of the cover plate away from the guard far enough to insure easy reciprocation of the blade; and for insuring the proper seating of the blade on the guard plate at the rear part of its width, the cover plate has about midway in its length an inwardly projecting stud, 117^f, 100 whose end when the cover plate is at closed position and stopped by the studs, 6^c, is spaced from the cover plate very slightly more than the blade thickness.

The lug, 117^e, adjacent to the bracket, 102, 105 has a housing, 117^g, for a coiled spring, 9^x, corresponding in function to the coiled spring, 9, of the other form, reacting against the pintle, 115, which intrudes for yieldingly holding the opposite lug, 117^e, of the cover 110 plate against the opposite bracket, 101. For engagement of the projection, 8^c, formed on that lug, 117^e, with the aperture, 11^a, formed in the bracket, 101, corresponding to the similarly designated aperture in the other 115 form.

The form shown in these Figs. 9 to 16 is readily assembled, the unitary member comprising the bracket, 102, tie plate, 103, and back flange, 112, is engaged with the cover 120 member by inserting the pintle, 115, in the spring housing, 117^g, of the lug, 117^e. The pinion is mounted on the stud, 104, the rack is engaged with the pinion, and the roll pintle at the side at which the rack teeth face 125 is engaged with the bracket, 101, at the end, and the assembled cover plate, 117, and unitary members, 101, 102 and 103, may then be readily placed in position on the guard plate upon which the parts are already as- 130

sembled, by simultaneously engaging the unengaged roll pintle in its bearing in the bracket member, 102, simultaneously with the engagement of the tie plate, 103, with the 5 studs, 104 and 105. The handle will then be screwed onto the threaded stud, 113, provided to receive it on the tie plate, and the device is in condition to receive the blade by folding back the cover plate as in the 10 other form, and engaging the blade by the slot, 7^c, with the studs, 6^c, and by one of the slots, 7^b, with the operating eccentric pin or crank pin, 5^b.

We claim:

15. 1. In a safety razor, in combination with a fixed guard and a blade having its cutting edge adjacent to the guard, a roller mounted in front of the guard; a crank and pitman operatively associated with the roller for reciprocation of the pitman crosswise of the cutting edge of the blade; a rack on the pitman; a pinion engaged with the rack and having an abutment engaging a transverse slot in the blade for reciprocating the blade 20 by the rotation of the pinion.
20. 2. In a safety razor, in combination with a fixed guard and a blade mounted for reciprocation of the cutting edge adjacent to the guard; a roller mounted in front of the guard; a crank and pitman operatively associated with the roller for reciprocation of the pitman transversely of the cutting edge of the blade; a rack on the pitman; and operating connections between the pinion and 30 blade for converting oscillatory motion of the pinion into longitudinal reciprocation of the blade.
30. 3. In a safety razor, in combination with a fixed guard and a blade mounted for reciprocation of the cutting edge adjacent to the guard; a roller in front of the guard; a crank and pitman operatively associated with the roller for reciprocation of the pitman crosswise of the cutting edge of the blade, and operating connections from the pitman to the blade for converting the crosswise movement of the pitman into longitudinal movement of the blade.
40. 4. In a safety razor, in combination with a mount, a guard plate fixed on the mount, a blade mounted and guided for reciprocation on the outer face of the guard plate, a roller journaled on the mount at the forward side of the guard plate above the plane of the blade; a crank and pitman operatively associated with the roller for reciprocation of the pitman crosswise of the cutting edge of the blade, the pitman extending back under the guard plate; operating means under the 50 guard plate comprising means taking through the guard plate for reciprocating the blade, the blade having apertures for engagement of said operating means symmetrically situated with respect to a medial transverse line; whereby the blade may be re-

versed endwise for presenting either face to the surface to be shaved.

5. In a safety razor, in combination with a mount comprising a guard plate fixed on the mount; a blade mounted on the outer face of the guard plate and provided with means by which it is guided thereon for longitudinal reciprocation of the pitman crosswise of the cutting edge of the blade, the pitman extending back under the guard plate; operating connections under the guard plate having means projecting through the guard plate for engaging the blade to reciprocate it; a blade-retaining plate hinged to the mount rearward of the path of reciprocation of the blade and back of the plane thereof, and a spring-operated catch at the hinged side of the blade-retaining plate for engaging the plate with the housing at blade-retaining position of the plate.

6. In the construction defined in claim 5 last foregoing, the retaining plate having lugs at the ends extending back for embracing the mount for pivoting the blade thereto, the catch device comprising a spring reacting between the mount and one of the lugs for yieldingly thrusting the plate endwise to the limit of play between the lugs and the mount, the lug at the opposite end and the mount having, one, a projection, 95 and the other, a recess for engaging the projection disengageably by thrust of the plate against the reaction of the spring.

7. In a safety razor in combination with a fixed guard, a blade seated for reciprocation on the guard and means on the guard for guiding it in such reciprocation; a roller carried by the guard for rolling contact with the surface to be shaved; a crank and pitman operatively associated with the 100 roller for reciprocation of the pitman transversely of the direction of reciprocation of the blade on its seat, and operating connections from the pitman to the blade for converting said transverse movement of the pitman into longitudinal movement of the 105 blade.

8. In a safety razor having a guard plate for seating a reciprocating blade; a roller carried by the guard plate for rolling contact with the surface to be shaved; a cover member between which and the guard plate the blade is seated for reciprocation; bearing parts for the opposite ends of the roller and for the opposite hinge pintle of the 110 cover member, one of said bearing parts being rigid with the guard plate, and the other adapted to be engaged with the cover member, studs mounted in the guard plate and a plate rigid with said second mentioned bearing member adapted to be engaged with said stud; operating connections from the roller member for reciprocating the blade on the guard plate, comprising 115 an operating projection which protrudes 120

125

130

- through the guard plate for engaging the blade, whereby the cover plate and parts assembled thereon may be applied to the guard plate and parts assembled thereon for 5 complete assembling of said device, and a hinge pintle for the opposite end of the cover plate, engageable therewith and with the fixed bracket on the guard plate, for the completion of such assembling for securing 10 the parts together.
9. In a safety razor, in combination with a fixed guard, a blade seated for reciprocation on the guard; means on the guard plate for guiding it in such reciprocation; 15 operating means for reciprocating the blade, situated at the opposite side of the guard from that on which the blade is seated and guided, and comprising a blade-engaging projection extending through an aperture 20 in the guard to reach the blade, and a hinged cover plate for retaining the blade on the guard, said blade-guiding projections extending through the blade for stopping the cover plate and spacing its forward edge away from the guard to insure 25 free space for the reciprocation of the blades between the guard and cover plate.
10. In a safety razor, in combination with a fixed guard, a blade seated for reciprocation on the guard; means on the guard plate 30 for guiding it in such reciprocation; operating means for reciprocating the blade, situated on the opposite side of the guard from that on which the blade is seated and 35 guided, and comprising a blade-engaging
- projection extending through an aperture in the guard to reach the blade; an imperforate hinged cover plate for retaining the blade on the guard, and means for spacing it off therefrom at the forward edge adequately to permit free reciprocation of the blade between the guard and cover plate, and a stud projecting inwardly from the retaining plate near the rear edge and middle part of the length of the blade for retaining the blade close to the seat at said rear part of its width. 40
11. In a safety razor, in combination with a fixed guard and a blade mounted for reciprocation of its cutting edge adjacent to 50 the guard; a roller mounted in front of the guard; a crank and pitman operatively associated with the roller for reciprocation of the pitman transversely of the cutting edge of the blade; a rack on the pitman and operating connections between the pitman and blade for converting the oscillatory motion of the pinion to longitudinal reciprocation of the blade, and guide means for the pitman comprising a stud having a transverse 55 slot at one side for the edge of the pitman, the opposite sides of the slot being cut away to reduce them to V-shaped projections between which the pitman is guided in its reciprocation. 60

In testimony whereof we have hereunto set our hands at Chicago, Illinois, this 29th day of June, 1920.

LEANDER H. LA CHANCE.
GEORGE BROWNING.
